UNITED STATES PATENT OFFICE.

EDWARD H. ANGIER, OF FRAMINGHAM, MASSACHUSETTS.

CRINKLING PAPER.

Application filed July 16, 1925. Serial No. 44,004.

This invention comprises a novel method of crinkling paper and apparatus for practicing the same and also a technically new product the making of which is made possible thereby. Such product comprises paper in webs of indefinite lengths, such as the usual mill rolls of paper, having a great amount of expansibility in the transverse direction, for instance, through crinklings 5 extending longitudinally of the web or parallel to the grain of the paper.

My invention will be best understood by reference to the following description taken in connection with the accompanying drawings wherein is shown in a partly diagrammatic manner suitable apparatus for practicing the method which is the subject of the invention and for producing the novel product. In these drawings:

20 Fig. 1 is a diagrammatic view showing a principal portion of the apparatus in longitudinal section;

Fig. 2 is a section on the line 2—2 of Fig. 1; and

25 Fig. 3 is a plan of the principal portion of the apparatus with parts successively broken away.

My invention will be readily understood by a description of the particular apparatus 30 chosen for illustration by way of example in these drawings and of the method of its operation although it will be understood that the invention is by no means limited to the construction or arrangement of parts shown.

35 Referring to Fig. 1 of the drawings, the paper p to be crinkled may be in the form of a web drawn from the mill roll 5. The paper may be either craped dry or suitably prepared by moistening and I have herein 40 shown it as led through a suitable moistening or saturating tank 7 before proceeding to the crinkling apparatus proper. Where considerable resiliency is desired in the finished product I prefer to moisten the paper 45 or to operate on moist partly finished paper stock. Suitable re-winding means, indicated diagrammatically at 8, may be utilized for rolling up the paper web after it is crinkled.

50 In the form of the invention shown the paper web p is deposited upon a suitable yielding body and shortening of this body is then effected so as to effect a concomitant shortening or compression of the paper web, herein a transverse compression, which 55 causes it to occupy a smaller area and thus

brings it into a crinkled or craped form, suitable provision being made for preventing the paper from merely folding or buckling into relatively large pleats or folds and insuring that the compression thereof shall 60 effect a more or less irregular and fine crinkling as distinguished from relatively large and regular foldings or corrugations. The operation is preferably so conducted that, while the product is fluted or corrugated, because of the multiplicity and fineness of the 65 flutings it may be handled practically as a flat and uniform web. Although made in paper which is limber or flaccid, as contrasted, for example, with straw-board or the like, the flutings will be self-maintaining 70 and permanent against the strains of ordinary handling, but they provide for a wide range of expansibility in the paper to fit it 75 for various practical uses.

Referring to the apparatus herein illustrated, the paper p is deposited upon one of the runs or leads of a belt 9 which may be supported from beneath by the support 11 and the paper may be confined thereagainst by the opposed run of a similar belt 13, this run being likewise held against deflection by a support 15. The belts are driven as is indicated in Fig. 3 by the showing of a drive pulley 17 on the shaft of one of the belt-carrying pulleys and of the gears 19 gearing together the two belts so that the opposed runs thereof move at the same linear speed and carry along between them the paper web p from right to left in Fig. 1 and closely 80 confine it.

The belts 9 and 13 may be made of rubber or other elastic material and as best indicated in Fig. 3 the edges thereof are guided in converging lines so that at the intake end of the belts, the upper end viewing Fig. 3, the body of the belt is relatively extended but it is permitted elastically to contract and gradually shorten in transverse dimension as it approaches the opposite end of its run. This may be effected in any convenient manner but I have herein, (see Fig. 2) shown the belts as provided with enlarged inextensible edge or bead portions 21 which engage the 95 edges of the supports 11 and 15 and the ends of the belt-carrying rolls. The rolls at the intake end of the machine are wider than the rolls at the opposite end and the supports 11 and 15 taper, as indicated in Fig. 3. The belts are thus held extended at the in- 100 105 110

take end of the machine and permitted gradually to collapse or contract in their forward travel.

The paper web *p* enters between the 5 stretched out portions of the belts and is firmly held throughout its width therebetween and frictionally gripped by the rubber. As the belts contract the paper tends to be shortened with them and is compressed 10 laterally. Since the rubber frictionally grips the paper throughout its width, this compressing action is not a mere pressing together of the two edges of the paper but a uniform action exerted throughout its width 15 tending to densify the same. By this compressive action the paper is forced into a multiplicity of fine irregular folds or crinklings. It will be noted that the paper is held against substantial deflection from a 20 plane. It is, of course, clear that in being crinkled it departs from a plane in the geometrical sense but it is nowhere free to move any considerable distance, nor is there any path of least resistance defining a location 25 where it could most readily break away from the surface of the belt against which it is pressed. The paper is thus forced by the compression, particularly when the compression is uniformly applied throughout its 30 width in the manner described, to crumple uniformly into small crinkles and it is nowhere free to lift away from the surface of one of the belts in a large fold.

It will be apparent that the amount of 35 crinkling to produce a finished product with the desired percentage of stretch may be regulated by varying the extent and rapidity of the narrowing to which the belt or equivalent member is subjected. For certain uses 40 a paper having an expansibility of twenty to thirty percent is desirable and such a degree of expansibility may be provided for by the means described. Hitherto an unbroken web of paper in effect flat and uniform and 45 with a substantial degree of transverse expansibility, say one-eighth or more, has not been produced. Corrugations as described in British patents to Parrish 1,610 of 1871, and to Mellersh-Jackson 138,740 have been 50 made parallel to the grain of paper but in sheets cut from a web previously craped transversely to the grain. Furthermore, such corrugations are not permanent in flaccid paper or/and the corrugated product is 55 sensibly such instead of being in effect flat. Herringbone craping as described in British patent to Otaka Fabric Company 156,448 has been practiced chiefly for its ornamental effect and has provided only a slight degree 60 of transverse expansibility.

In the example of the invention chosen 65 for purposes of illustration the process is a continuous one which gradually transversely compresses the paper into crinklings con-

through the mechanism and may be practiced as indicated on a long paper web of indefinite length such as the ordinary mill roll of paper. The production of stretchable paper hitherto has been effected by a craping 70 process which, when applied to long webs of paper, has been capable only of producing crapings extending in a generally transverse direction across the width of the web, the paper being crowded back on itself or shortened in the direction of the length of the web. Herein, on the contrary, as illustrated at the bottom of Fig. 3, the crinklings extend substantially longitudinally of the 75 web of paper. In the prior processes if the direction of the crapings were considered the longitudinal direction of the paper, the length of the pieces of paper which could thus be produced was limited to the width 80 of the original roll of paper as produced by the paper making machine, that is, a matter of a few feet instead of a matter of a great many yards as in the present case.

Furthermore, in the production of paper 85 the fibers felt together and extend in a direction generally parallel to the passage of the paper through the paper making machine so that a web of paper has a grain extending longitudinally and a sheet of paper is stronger lengthwise of this grain than it is transversely thereof. In the example shown the crinklings of the paper extend parallel to the grain and thus the expansibility of the 90 paper due thereto is transverse to the grain and the resistance to bursting provided by the yielding resistance of these crinklings 95 is utilized to supplement the strength of the paper in its weaker direction.

By way of illustration and without attempting a full enumeration I will refer 100 briefly to some of the advantageous uses of longitudinally crinkled paper. Such paper is particularly desirable for use in making bags and such bags may be constructed from a continuous web of paper on present types 105 of bag making machines and will have the crinklings extending from the top to the bottom of the bag instead of circumferentially thereof. Particularly when the crinklings are as herein described parallel to 110 the grain of the paper, this is most desirable as the full strength of the paper will be available between the bottom and the neck 115 of the bag to support the weight thereof while the bag will be expansible to permit 120 bulging of the same.

Another extensive use for crinkled paper 125 is the production of liners for barrels as, for example, is illustrated in Patent No. 764,545, July 12, 1904, to Arkell. Paper longitudinally craped may be folded and seamed lengthwise into a continuous tube in a very simple manner and the tubes may be cut off at any length desired to provide barrel liners with 130 the crinklings running vertically of the bar.

rel so that they may expand to fit the bilge. Furthermore, if the grain of the paper is likewise longitudinal, the full strength is available when one end of the liner is turned 5 down over the chine of the barrel as illustrated in that patent, resisting the tendency of the paper to tear at the chine while the crinklings permit the circumferential expansion facilitating this turning over of the 10 end of the liner.

I have described in detail the particular mechanism herein illustrated as an example of a suitable means of carrying out my invention. It will be understood that the 15 closure is diagrammatic and that the apparatus used might widely differ in construction and arrangement and without departing from the essential principles underlying my invention. What I claim as new and desire 20 to secure by Letters Patent I shall express in the following claims. By the word "plane" in these claims, as in the phrase "against substantial deflection from a plane", I refer to the surface in which the part of 25 the paper under consideration lies and which may be considered as defined by the paper because of the extended, sheet-like character of the latter. If the paper lies flat, this approximates a geometrical plane, 30 but obviously the process is not essentially altered if the surface is more or less curved.

Claims:

1. An unbroken paper web of indefinite 35 length having crinklings extending longitudinally thereof and providing for elastic expansibility of the web transversely thereof.

2. An unbroken paper web of indefinite 40 length having its grain extending longitudinally thereof and having crinklings extending substantially parallel to the grain and providing for elastic expansibility of the web transversely thereof.

3. An unbroken web of paper of indefinite 45 length transversely compacted in a multiplicity of fine flutings extending lengthwise of the web, which flutings are self-maintaining and provide a web in effect uniform and flat, said web being transversely expansible by an eighth of its width or more.

50 4. An unbroken web of paper of indefinite length having its grain extending longitudinally thereof and gathered in a multiplicity of fine flutings extending generally parallel to the grain, which flutings are self-maintaining and provide a web in effect uniform and flat, said web being transversely expansible by an eighth of its width or more.

55 5. An unbroken web of flaccid paper of indefinite length compacted by a multiplicity of fine flutings to provide a web in effect uniform and flat and expansible transversely through extension of said flutings by an eighth of its width or more.

60 6. A method of crinkling paper which 65 comprises holding the paper against an ex-

tended surface and permitting the surface to contract.

7. A method of crinkling paper which comprises holding the paper confined substantially in a plane between extended elements and permitting the elements to contract in said plane. 70

8. A method of crinkling paper which comprises leading the paper over a moving length of material which is gradually shortening laterally and confining the paper thereto against substantial deflection therefrom. 75

9. A method of crinkling paper which comprises leading the paper between moving lengths of material which are gradually shortening laterally and which confine the paper closely therebetween. 80

10. A method of crinkling paper which comprises confining the paper closely to the surface of a body and effecting substantially uniform shortening of said body. 85

11. A method of crinkling paper which comprises confining the paper closely between opposed bodies and effecting substantially uniform shortening of said bodies. 90

12. A method of crinkling paper which comprises advancing the paper closely confined against a yielding body and effecting gradual transverse shortening of the body 95 concurrently with the advance of the paper.

13. A method of crinkling a paper web characterized by subjecting the web to transverse compression while holding it against substantial deflection from a plane. 100

14. A method of crinkling a paper web characterized by subjecting the web simultaneously throughout its width to transverse compressive forces while holding it against substantial deflection from a plane. 105

15. A method of crinkling a paper web which comprises advancing the paper longitudinally and progressively subjecting it in a portion of its path to transverse compression exerted thereon throughout its width while holding it against substantial deflection from a plane. 110

16. A method of crinkling paper which comprises effecting a substantially uniform frictional adherence of the paper to a support, maintaining the paper thereagainst against substantial deflection from a plane and causing the support and paper to occupy a smaller area by a substantially uniform collapse of the support. 115

17. A method of crinkling a long paper web which comprises subjecting the extended paper to a friction tending to transversely compress it while maintaining it against substantial deflection from a plane. 120

18. Crinkling mechanism comprising a yielding body, means to confine paper closely thereagainst and means to effect substantially uniform shortening and extension of said body. 125

19. Crinkling mechanism comprising means for guiding a paper web, a yielding body over which the paper passes, means to confine the paper thereto, means for advancing the paper and means to effect a gradual transverse shortening of the body concurrent with the advance of the paper.
20. Crinkling mechanism comprising means for guiding a paper web, an element 10 over which the web leads, means to confine the paper to a surface thereof and against substantial deflection from a plane and means for effecting alternate expansion and contraction of said element.
- 15 21. Crinkling mechanism comprising an elastic belt, means for maintaining edges of said belt in converging lines whereby a run of the belt narrows in travel and means to confine paper closely to the surface of said 20 run.
22. Crinkling mechanism comprising an elastic body, means for alternately elongat-
- ing and shortening the same and means to hold paper thereto to partake of the shortening movement without substantial deflection from a plane. 25
23. Crinkling mechanism comprising a pair of transversely elastic belts having opposed runs adapted to confine paper therebetween, means for maintaining the edges 30 of said runs in converging lines and means for driving the belts.
24. Crinkling mechanism comprising a pair of belts having opposed runs to receive paper therebetween, said belts having elastic bodies, guides disposed in converging lines adjacent said runs and cooperating with the edges of the belts to control the extension of the bodies thereof and means for driving the belts. 35

In testimony whereof, I have signed my name to this specification.

EDWARD H. ANGIER.
